REMOVABLE SLAT METAL AWNING

James R. Clark and Charles T. Flavin,
Middletown, Ohio

Application December 1, 1949, Serial No. 130,478

2 Claims. (Cl. 20—57.5)

1

This invention relates to awnings of the Venetian blind type, and in particular an awning formed with a pair of stringers held in spaced relation by rods extended through the ends thereof and provided with slat receiving recesses in the outer edges, and a plurality of slats, triangular shaped in cross section removably mounted in the recesses of the stringers.

The purpose of this invention is to provide an improved type of awning that may be shipped before assembly and that is formed with V-shaped slats which diffuse reflected light without reducing the heat intercepting characteristics thereof.

Various types of awnings have been provided using metal strips of different designs but metal awnings of this type are heavy and when shipped assembled are difficult to handle. Numerous attempts have also been made to ventilate awnings of this type to permit air to escape through the awning without reducing the efficiency of the awning. With these thoughts in mind this invention contemplates an awning in which triangular shaped slats are removably mounted in recesses in stringers and the stringers are held together by rods with the stringers clamped against shoulders of the rods by lock nuts.

The object of this invention is, therefore, to provide means for forming an awning with continuous ventilating openings therethrough and in which slats providing the body of the awnings are freely positioned in recesses in stringers or supporting elements.

Another object of the invention is to provide an awning of the collapsible type in which the parts are shipped in a compact unit and readily assembled without permanently attaching the parts.

A further object of the invention is to provide an awning of the collapsible type and having permanent ventilating openings therethrough which is of a simple and economical construction.

With these and other objects and advantages in view the invention embodies a pair of parallel bars with recesses in the edges of one of the sides thereof, with slats freely positioned in the recesses and with the stringers clamped in spaced relation by rods extended therethrough.

Other features and advantages of the invention will appear from the following description taken in connection with the drawings wherein:

Figure 1 is a longitudinal section through the awning taken on line 1—1 of Figure 2.

Figure 2 is a front elevational view showing the awning.

2

Figure 3 is a detail illustrating one of the slats of the awning.

Figure 4 is a detail showing the shape of the recesses in the edges of the stringers.

5 Figure 5 is a detail showing one end of one of the slats in combination with a stringer, said detail being a section taken on line 5—5 of Figure 1 with part of the slat broken away.

Figure 6 is a cross section through one end of 10 the awning taken on line 6—6 of Figure 1 showing one of the rods for clamping the stringers in spaced relation.

Referring now to the drawings wherein like 15 reference characters denote corresponding parts

15 the improved awning of this invention is formed with slats 10 carried by stringers 11 and 12 with the stringers secured in spaced relation by rods 13 and 14 in which the stringers are clamped against shoulders 15 at the ends of the rods 13 and 14 by lock nuts 16 on threaded studs 17 at the ends of the rods.

The ends of the stringers 11 and 12 are provided with openings 18 in which the studs 17 are positioned and the outer edges of the stringers 25 are provided with recesses 19 having converging sides 20 and 21, as shown in Figure 4. The inner walls of the recesses, as indicated by the numeral 19 slope inwardly, the upper end walls 20 slope downwardly and the lower walls 21 slope upwardly whereby with the V-shaped slats 10 pressed together as they are inserted in the recesses the sides thereof spring outwardly with the upper web 22 bearing against the wall 20 of the recess and the lower wall or base, as indicated 30 by the numeral 10 bearing against the short wall 21 of the recess. The upper web or section 22 of the slat is provided with notches 23 and 24 that receive the edges of the stringers 11 and 12, as illustrated in Figure 1. To facilitate gripping 35 of the stringers by the slats the upper walls or webs 22 of the slats are arcuate, the outer part thereof being formed on a radius as shown in the drawing. The lower section to which the numeral 10 refers is illustrated as being flat.

40 It will also be understood that the slats may be of any shape or design and may be formed of corrugated instead of flat material and the width of the sections may also be varied to change the positions of the slats in the stringers.

45 The awning as illustrated and described may be mounted with the usual awning supporting elements or may be supported by any suitable means.

With the parts arranged in this manner the 50 V-shaped slats, the stringers 11 and 12 and the

rods 13 and 14 may be placed in parallel relation in an elongated box, carton, or the like for shipping and when it is desired to set up the awning for use the ends of the stringers are clamped on the rods 13 and 14 by the lock nuts 16 and with the stringers held in position the slats 10 are squeezed together and snapped into the recesses 19 of the stringers.

With the slats positioned in this manner ventilating openings are provided continuously through the surface of the awning and with the slats formed in the V-shaped light passes through the awning whereas the direct sun rays which carry heat are intercepted unless the sun is in such a position that the light rays therefrom are substantially parallel to the webs 22 of the slats. These openings are comparatively small and the sun would remain in this position a relatively short period of time.

It will be understood that modifications may be made in the design and arrangement of the parts without departing from the spirit of the invention.

What is claimed is:

1. In a collapsible awning, the combination which comprises a pair of supporting stringers with spaced recesses in the outer edges and having openings therethrough spaced from the ends thereof, rods having threaded studs on the ends positioned between the stringers with the studs extended through the openings in the stringers, lock nuts threaded on the studs of the rods for clamping the stringers against the shoulders of the rods, and slats V-shaped in cross section having upper and lower webs with outwardly extended vertexes positioned in the re-

cesses of the stringers with the webs engaging the upper and lower ends of the recesses, the upper webs of said slats being arcuate and having notches in the edges thereof to receive corresponding edges of the stringers.

2. An awning having a plurality of spaced stringers with spaced recesses in the outer edges, the inner walls of said recesses sloping upwardly and inwardly, the upper end walls sloping downwardly and inwardly from the edges of the stringers and the lower end walls of the recesses sloping upwardly and inwardly, means retaining the stringers in spaced relation, and slats V-shaped in cross section having upper and lower webs with outwardly extended vertexes positioned in the recesses of the stringers with the webs engaging the upper and lower ends of the recesses, the upper webs of said slats being arcuate and having notches in the edges thereof to receive corresponding edges of the stringers.
